Primary Examiner — Karen E. Eldridge Powers*Assistant Examiner* — Jasmine Mlinarcik(74) *Attorney, Agent, or Firm* — Wilson Sonsini Goodrich & Rosati(57) **CLAIM**

The ornamental design for a hat with a rectangularly-shaped electronic display screen, as shown.

DESCRIPTION

FIG. 1 shows a perspective view of a hat with a rectangularly-shaped electronic display screen;

FIG. 2 shows a front elevation view of the hat with a rectangularly-shaped electronic display screen;

FIG. 3 shows a side elevation view of the hat with a rectangularly-shaped electronic display screen; and, FIG. 4 shows a top plan view of the hat with a rectangularly-shaped electronic display screen.
